JOHN F. O'CONNOR, OF CHICAGO, ILLINOIS, ASSIGNOR TO WILLIAM H. MINEE, OF CHAZY, NEW YORK.

DRAW-BAR AND YOKE CONNECTION.

1,286,738.

Specification of Letters Patent.

Patented Dec. 3, 1918.

Application filed August 20, 1917. Serial No. 187,291.

To all whom it may concern:

Be it known that I, JOHN F. O'CONNOR, a citizen of the United States, residing at Chicago, in the county of Cook and State of Illinois, have invented a certain new and useful Improvement in Draw-Bar and Yoke Connections, of which the following is a full, clear, concise, and exact description, reference being had to the accompanying drawings, forming a part of this specification.

This invention relates to improvements in draw bar and yoke connections.

One object of my invention is to provide a detachable draw bar and yoke connection so arranged that old yoke straps of the riveted type may be reemployed with consequent saving in cost of material to the railroads.

Another and more specific object of the invention is to provide a detachable connection of the type above specified wherein is employed a hollow head for receiving the draw bar butt, a yoke strap, removable pins for connecting the head, draw bar and strap, and means for placing the pins under double shear to thereby increase the strength of the connection.

In the drawing forming a part of this specification, Figure 1 is a side elevation of a draw bar and yoke showing my improvements in connection therewith. Fig. 2 is a horizontal sectional view taken on the line 2-2 of Fig. 1. Fig. 3 is a vertical, sectional view taken on the line 3-3 of Fig. 1. Fig. 4 is a longitudinal, vertical, sectional view illustrating another embodiment of the invention. And Fig. 5 is a perspective view illustrating a portion of the arrangement shown in Fig. 4.

Referring to the arrangement shown in Figs. 1, 2 and 3, A denotes a standard draw bar; B a wrought-iron U-shaped yoke strap of the usual riveted type; C a hollow rectangular cast head or hood; D-D connecting pins; and E a short coupler key.

The draw bar A is of the standard type having the usual pair of rivet receiving holes 10-10, upper and lower shoulders 11-11, and in this instance, coupler key slot 12.

The yoke B, as above indicated, is of the old riveted type, having upper and lower arms 13 and 14, integral rear connecting portion 15, and filler 16. At the forward ends, the arms 13 and 14 of said yoke B are also

provided with standardly spaced rivet receiving holes 17-17.

The head or hood C is adapted to receive therewithin the butt of the draw bar with the forward ends of the yoke arms positioned between the upper and lower walls of the head and the butt. Said head C, as shown, has upper and lower walls 18 and 19 and side walls 20-20, flared at their forward ends, as indicated at 21-21. The upper and lower walls 18 and 19 are also provided with standardly spaced perforations 22-22 and the side walls are slotted as indicated at 23 to accommodate the short coupler key E.

The parts may be assembled as follows: The head C is slipped over the forward ends of the arms of the yoke B after which the butt of the draw bar is inserted within the head and all of the holes or perforations 10, 17 and 22 brought into alignment. The coupler key E is then inserted after which the pins D-D are dropped through from the top, and it will be noted that the forward pin D will retain the key E in position, said forward pin D engaging in a notch 24 in said key E. The pins D may be held from accidental disengagement by any suitable means, such as the cotters 25.

With the arrangement above described, it is obvious that I obtain a detachable connection between the draw bar and yoke without modification of either. In addition, by employing the coupler key E, the pins D are placed in double shear at both top and bottom, due to the fact that movements of the draw bar are communicated to the head C through the key E, as will be understood.

In the construction illustrated in Figs. 4 and 5, the draw bar A' is of that standard type not having a coupler key slot, of which there are many thousands now in service. It is however provided with the usual standardly spaced rivet receiving holes 110-110 and the usual upper and lower shoulders 111-111. The strap B' is, or may be, the same as that shown in the other figures.

The head or hood C' is of hollow rectangular formation having upper and lower walls 118 and 119 and side walls 120-120. The upper and lower walls of the head and the forward ends of the yoke arms are provided with aligned holes or perforations so that when the parts are properly assembled pins D'-D' may be inserted therethrough the same as in the other construction.

In the arrangement shown in Figs. 4 and 5, to obtain the double shear effect on the pins D'-D', I employ two transversely extending keys E'-E'. As clearly shown in Fig. 5, these keys E' are notched on their inner faces, as indicated at 30, so as to fit over the shoulders 111-111 of the draw bar butt and the side walls of the head C' are suitably slotted to accommodate the ends of said keys E' when located in alignment with the upper and lower shoulders of the draw bar butt.

In assembling the structure shown in Figs. 4 and 5, the head C' is first slipped over the draw bar butt and the keys E'-E' placed in position. The head C' is then moved rearwardly until the draw bar shoulders 111-111 engage in the recesses 30 of the keys E' which will hold said keys E' in proper position against lateral movement. The ends of the yoke strap are then inserted and finally the pins D' applied whereupon all the parts are locked in operative position. In this construction it will be noted that the pins D' are also under double shear due to the fact that there is shouldered engagement between the draw bar and the head C' under draft.

Although I have herein shown and described what I now consider the preferred method of carrying out my invention, I do not intend to be limited thereby but contemplate all changes and modifications that come within the scope of the claims appended hereto.

I claim:

1. In a device of the character described, the combination with a standard draw bar and a yoke strap, of a hollow head within which the draw bar butt and the forward

ends of the strap arms are received, said arms being disposed between the walls of the head and the draw bar butt and all of said members having alined holes, pins extending within said holes for detachably connecting the draw bar, head and strap, and additional means for operatively connecting the head and draw bar under draft to thereby place said pins under double shear.

2. In a device of the character described, the combination with a standard draw bar and a yoke strap, of a hollow head within which the draw bar butt and the forward ends of the strap arms are received, said head, draw bar and strap arms having alined holes, pins extending within said holes, and additional means for operatively connecting the draw bar and head under draft, said means including a transverse key having shoulder engagement with both the head and the draw bar, one of said pins engaging said key and preventing transverse movement thereof.

3. In a device of the character described, the combination with a standard draw bar and a U-shaped yoke strap, of a hollow hood within which the forward ends of the arms of the strap and the draw bar butt are received, all of said members having alined holes, pins extending through said holes, the side walls of said head and the draw bar being slotted, and a transverse key extending through said slots for effecting connection between the draw bar and head.

In witness that I claim the foregoing I have hereunto subscribed my name this 29th day of July, 1917.

JOHN F. O'CONNOR.
